UNITED STATES PATENT OFFICE.

ROBERT L. MAPSON, OF SAN DIEGO, CALIFORNIA, ASSIGNOR OF ONE-HALF TO LORENZO SPERBECK, OF LA MESA, CALIFORNIA.

VALVE-RELEASING DEVICE.

1,222,229.

Specification of Letters Patent. Patented Apr. 10, 1917.

Application filed March 20, 1916. Serial No. 85,263.

To all whom it may concern:

Be it known that I, ROBERT L. MAPSON, a citizen of the United States, residing at San Diego, in the county of San Diego and State 5 of California, have invented certain new and useful Improvements in Valve-Releasing Devices, of which the following is a specification.

My invention relates to a device to facilitate 10 the releasing and removing valves for internal combustion engines, and the objects of my invention are: First, to provide a device of this class in which the handles for operating the same are up in a position readily 15 accessible to the operator and out of the way of the various parts usually adjacent the valves; second, to provide a device of this class in which the moving valve engaging parts move and operate in alinement, thus 20 minimizing the liability to bend the valve stem in releasing and removing the same; third, to provide a device of this class which may be locked, thus holding the spring in various compressed positions as desired and leaving 25 the operator the use of his hands for removing the washer, key or nut on the bottom of the valve stem; fourth, to provide a device of this class in which the lower engaging member is adjustable for different sized valve 30 stems and may be secured onto the valve washer so there is no danger of its slipping off; and fifth, to provide a device of this class which is simple and economical of construction, durable, easily operated and will 35 not readily get out of order.

With these and other objects in view as will appear hereinafter, my invention consists of certain novel features of construction, combination and arrangement of parts 40 as will be hereinafter described in detail and particularly set forth in the appended claims, reference being had to the accompanying drawings and to the characters of reference thereon which form a part of this 45 specification, in which:

Figure 1 is a side elevational view of my device complete showing by solid lines its position in connection with a valve with the spring compressed ready for the removal of 50 the washer, pin or nut and showing by dotted lines the position of a portion of the device when the spring is extended before being compressed. Fig. 2 is a fragmentary top view of the valve stem and valve washer en-

gaging portion of the device, and Fig. 3 55 is a fragmentary side elevational view of my device shown on the opposite side to that of Fig. 1.

Similar characters of reference refer to similar parts throughout the views. 60

The support 1, links 2, operating lever 3, locking lever 4 and lower end engaging member 5 constitute the principal parts of my valve releasing device.

The support 1 is preferably a flat metallic bar provided with a pointed lower end 1^b which is adapted to fit into the usual center-punch hole in the top of the valve. On its upper end is mounted a handle 1^b. Some distance from the lower end is pivotally mounted thereon two links 2 one on each side thereof. Some distance above this pivotal mounting is pivotally mounted thereon a handle 3 and on the opposite side a link 3^a. Pivotally mounted between this 75 operating lever 3 and the handle 1^b is the locking lever 4 shaped as shown best in Fig. 1 of the drawing which is provided with a plurality of teeth 4^a which engage a rigid dog 3^b mounted between the hand lever 80 and link 3^a said teeth are inclined in one direction so that they engage with said dog in one direction but slide over the same when moved in the opposite direction. Connecting the lever 4 with the support 1 is a tension spring 4^b tending to hold the teeth in engagement with the dog 3^b. The upper end of said lever 4 is provided with a finger hold 4^c which is adapted to be operated by the small finger of the hand of the operator 90 holding the handle 1^b. The hand lever 3 extends normally in a horizontal position a short distance and is then bent upwardly at 3^c and on its upper end is provided a handle 3^d. Pivotally mounted between the hand 95 lever 3 and the link 3^a near the bend in the handle 3^d is the upper end of the lower end engaging member 5 and said member 5 is also pivotally mounted between the extended ends of the two links 2. The inwardly extending 100 end of the member 5 is bifurcated and preferably tempered so as to provide sufficient inherent spring. It is provided with a screw 5^a adapted to spring it together for adjusting it to different sized washers. It 105 is provided with a circular shaped extended end 5^b and with recesses 5^c adapted to allow the valve washer to fit therein and the screw

5^a is turned inwardly. This extended end clamps onto the washer, thus preventing its slipping.

Though I have shown and described a 5 particular construction, combination and arrangement of parts, I do not wish to be limited to this particular construction, combination and arrangement but desire to include in the purview of my invention, the 10 construction, combination and arrangement of parts substantially as set forth in the appended claims.

It is obvious that with this construction there is provided a valve releasing and re- 15 moving device in which the operating parts are up out of the way of the various parts usually adjacent the valves and are readily accessible to the operator, that the device may be locked holding the spring in cer- 20 tain compressed positions as desired and the device will be supported in the position as shown in Fig. 1 of the drawings and the operator's hand will be free to remove the washer, key or nut on the bottom of the 25 valve stem after which by pressure on the finger hold 4^a of the lever, the handle 3^a will be moved downwardly in the position shown by dotted lines and the device re- 30 moved after which the valve may be re- moved from its position, that the bifurcated portion controlled by the screw 5^a provides for adjustment for different sized washers 35 on the valve stem, that the device is simple and economical of construction, durable, easily operated and will not readily get out of order.

Having thus described my invention what I claim as new and desire to secure by Letters Patent, is:

40 1. In a device of the class described, the combination of a stationary or supporting member adapted to fit the top end of a valve stem, a handle on the upper end for sup- porting it in a normally vertical position,

link members pivotally mounted thereon 45 and spaced apart from each other, a movable member spaced apart from said stationary member and pivotally mounted between said links in their spaced relation and means for moving said movable member up- 50 wardly and downwardly relatively to said stationary member.

2. In a device of the class described, the combination of a stationary or supporting member adapted to fit the top end of a valve 55 stem, a handle on the upper end for sup- porting it in a normally vertical position, link members pivotally mounted thereon and spaced apart from each other, a movable member spaced apart from said stationary member and pivotally mounted between said links in their spaced relation and means for moving said movable member upwardly and downwardly relatively to said stationary member and means for locking said movable 60 member in certain relative position to said stationary member.

3. In a device of the class described, the combination of a stationary or supporting member adapted to fit the top end of a valve 70 stem, a handle on the upper end for sup- porting it in a normally vertical position, link members pivotally mounted thereon and spaced apart from each other, a movable member spaced apart from said stationary member and pivotally mounted between said links in their spaced relation pro- 75 vided with adjustable means for fitting dif- ferent sized washers and means for mov- ing said movable member upwardly and 80 downwardly relatively to said stationary member and means for locking said movable member in certain relative position to said stationary member.

In testimony whereof, I have hereunto 85 set my hand at San Diego, California, this 13th day of March, 1916.

ROBERT L. MAPSON.
